UNITED STATES PATENT OFFICE.

MORRIS L. KAPLAN, OF HAZLETON, PENNSYLVANIA.

SHIRT-MAKING SYSTEM.

Application filed May 13, 1927. Serial No. 191,180.

My present invention relates to an improved shirt making system for use in the manufacture of men's shirts with collars attached as well as with detachable collars. The primary object of my invention is the provision of a detachable collar or an attached collar, for use with a shirt, that will not shrink after being laundered and prepared for the market, and will not shrink when laundered by the wearer of the shirt. By the utilization of the system of my invention in the manufacture of shirts and their collars, whether attached or detachable, the collar is shrunken to its minimum size before the garment is placed on the market, and therefore further shrinking of the collar is prevented. The goods, or material, from which the collar is made is shrunk to the required degree, before the pattern of the collar is laid out on the material, and the material of the shirt need not be shrunk at this time. In carrying out my invention the pattern for the various parts of the shirt, except the collar and collar bands, is laid out on the material, and from this material, a block or section of sufficient size to furnish the collar, is cut, then shrunk, and then marked with the pattern of the collar, and further treated, as will hereinafter be more fully pointed out and claimed.

In the accompanying drawings I have illustrated a lay out for a shirt (except for the collar) and a lay out or pattern for the collar, together with appliances or machines utilized in the shirt making system.

Figure 1 is a plan view showing a portion of a pattern for the various parts of a shirt, the pattern being laid on the goods or material from which the shirt is to be made, and a dotted section or blank is designated thereon for the collar pattern.

Figure 2 is a plan view of the section of material cut from the shirt pattern or lay. Figure 2^a is plan view of the collar pattern laid out on the piece of material previously cut from the main piece and shrunk.

Figure 3 is a perspective view of a rotary washing machine which may be used in the process of washing and shrinking the collar material, as 3.

Figure 4 is a perspective view of a drier or rotary extractor which may be used for extracting the moisture from the collar material after it has left the washer.

Figure 5 is a perspective view showing a press and the manner of pressing the collar-material before the collar pattern is laid out on the material. 60

While I have shown in the drawings only one lay for the shirt and a lay for the collar, it will be understood that the pattern for the shirt is usually cut in stacks or piles, and the pattern for the collar is also cut in 65 stacks or piles. Thus Figure 2^a shows a single piece of material with the lay for the collar on it, while Figure 5 shows a larger piece with space for a group of collar-patterns. 70

In Figure 1 the strip or piece of goods 1, from which the shirt is to be cut, is shown with the back, two fronts, cuffs etc. marked thereon. In marking the pattern on the strip of goods a space indicated by dotted lines 2 is provided, and this material is later cut from the strip into a blank 3 which is of sufficient size to permit it to be shrunken, and yet remain of proper dimensions to receive the collar pattern. This collar-section 3 is first shrunk to a smaller length as indicated by the section 4 in Figure 2^a, and the top and bottom parts of the collar as 5 and 6, and bands 7 are then laid out on this section as a collar pattern. 75 80 85

In carrying out my system of manufacturing the shirts and collars, I employ a rotary washer, as 8 into which the section 3, or a larger section 3^a, is introduced and laundered a period of time sufficient to shrink the material to the desired degree. After the material is removed from the washer, it is placed in a rotary drier or extractor 9 from which the moisture is extracted, and then the shrunken and dried section is ready to 90 95 be pressed in a presser or pressing machine 10. After leaving the pressing machine the section 3 or 3^a is ready to have the collar pattern applied thereto for guidance in cutting out the parts of the collar. 100

It will be understood that the lining material of the collar is also shrunk before being cut and incorporated in the collar, to prevent wrinkling and insure a smooth outer face or surface for the collar. 105

When the collar-material is placed in the press 10 the material is fitted lengthwise, in the machine and flat with the width of the goods between the two thumbs in Figure 5. Then as the material is laid flat on the press 110 it is slightly stretched between the thumbs, and as a result the length of the material is

- shrunk or shortened, and the press, when applied to the goods, maintains this shrunk-en condition. The goods are thus shrunk as they are laundered in the washer 8, and are manually shrunk also, as they are placed in the press for smoothing, and as a result the goods have been shrunk to the minimum condition and thereafter the collar maintains its designated and exact size.
- 10 When colored goods or material is used, it will be apparent that the colored blank 3 or 3^a may become bleached or "washed out" by being submitted to the washing process, in which event the collar would present a shade 15 of color different than the unlaundered colored shirt. To restore the original color and luster of the shrunken collar-blank, the latter is immersed in a liquid color-restoring material, which mixture may be a solution 20 of water, salt, and ink-blue. This mixture is thoroughly commingled to provide a liquid solution and the collar-material is immersed in and remains in this solution for the proper and correct time to restore the color 25 or shade, in order that the collar may present the same color and shade as the material of the shirt.
- Before the collar material is pressed, in order that a luster may be applied thereto, 30 after the color has been restored, the material is placed in a mixture of water and rice-
- starch and agitated while in a washing machine for a time, after which it is removed and partially dried, and the damp material is spread on the press, and smoothed out or 35 spread out flat for the press. Before the press is operated a liquid solution of water, borax and wax is applied to the material, and then when the latter is pressed the original color, luster, and appearance of the collar is provided like that of the shirt.
- Having thus fully described my invention, what I claim as new and desire to secure by Letters Patent is—
1. A system of shirt making comprising 45 the steps of first laying out a pattern of the parts in a piece of material, then cutting out a blank section of the material, subjecting said blank section to a shrinking treatment, and finally laying out a pattern for the collar 50 or the neck band of the shirt on said section.
2. A system of shirt making comprising (1) laying out a pattern of the parts in a piece of material with the exception of the collar parts and (2) leaving a blank section 55 in the piece of material (3) subjecting said blank section only to a shrinking treatment and (4) laying out a pattern for the collar of the shirt on said section.

In testimony whereof I have affixed my 60 signature.

MORRIS L. KAPLAN.
